(57) **CLAIM**

The ornamental design for a combined water timer and controller, as shown and described.

DESCRIPTION

FIG. 1 is a left, front perspective view of a combined water timer and controller;

FIG. 2 is a front end view thereof;

FIG. 3 is a back end view thereof;

FIG. 4 is a top plan view thereof;

FIG. 5 is a bottom plan view thereof;

FIG. 6 is a left side view thereof; and,

FIG. 7 is a right side view thereof.

The broken lines illustrate environmental structure and form no part of the claimed design.
